UNITED STATES PATENT OFFICE.

FRANK L. WAASER, OF BROOKLYN, NEW YORK, ASSIGNOR TO J. P. CUMINS, OF NEW YORK, N. Y.

VALVE.

SPECIFICATION forming part of Letters Patent No. 730,988, dated June 16, 1903.

Application filed September 3, 1901. Renewed November 14, 1902. Serial No. 131,409. (No model.)

To all whom it may concern:

Be it known that I, FRANK L. WAASER, a citizen of the United States, residing at Brooklyn, in the county of Kings and State of New York, have invented certain new and useful Improvements in Valves, of which the following is a specification.

My present invention pertains to feed-valves for hydrocarbon-burners, the construction and advantages of which will be herein-after set forth, reference being had to the annexed drawings, wherein—

Figure 1 is a front elevation of the valve; Fig. 2, an end view of the valve shell or casing; Fig. 3, a side elevation, partly in section; Fig. 4, a side elevation of the valve proper; Fig. 5, a top plan view of the same; Fig. 6, a front elevation of a modified form of construction; and Fig. 7, a side elevation, partly in section, of said modified form.

As is well known to those skilled in the use of hydrocarbons for fuel purposes, there will form upon the valved outlets employed a residuum composed mainly of paraffin or the like, which in time will stop the flow of the liquid fuel to a greater or less extent, thereby interfering with the proper feed of the fuel and the consequent regulation of the flame.

The present invention has for its object the provision of a self-clearing nozzle or valve; and it consists, broadly, in the employment of clearers or knives interposed between the seat and the regulating member, to which latter member a rotary movement is imparted to render the clearers or knives effective.

The invention is susceptible of various modifications, and in the accompanying drawings two forms are shown.

The embodiment illustrated in Figs. 1 to 5 will be first described. A denotes a shell or body provided with the usual inlet openings or ports B B' and with a conical discharge-outlet C, the face thereof being ground or otherwise finished to present a smooth surface. Working in conjunction with said outlet is a frusto-conical member D, the angle of its face being such that the inner portion thereof stands at a distance from the seat and approaches the same toward the outer end. The members in this form do not quite

come into contact, the space or opening left being determined by working conditions. A stem E, connected to the frusto-conical member, extends through a stuffing-box F to the outside of the shell or casing A, and to said stem is connected a rocker arm or lever G, which in turn is connected to a movable portion of an engine or other source of motion. A pair of diametrically-arranged knives or clearers H are secured within slots or channels formed in the seat, while a second pair of knives or clearers I are likewise secured to and carried by the conical member. The knives or clearers are of such form and dimensions that the pair H bear directly upon the face of the conical member, while the other pair I work over the seat. When a rocking motion is imparted to the arm G, the rotary reciprocating motion will be imparted to the conical member, and as a consequence the knives or clearers will sweep over the surface of the conical member and the seat, cutting or scraping off any deposit which may tend to accumulate thereon, the loosened substance, if any has accumulated, to be freed, being carried out by the hydrocarbon, which is forced through the valve under more or less pressure.

The modified form shown in Figs. 6 and 7 will now be described. In said figures, a denotes the shell or casing, carrying a bonnet b. The shell or casing is formed with an inlet c and a conical discharge-outlet d. A conical valve e is employed, the stem f thereof extending through a stuffing-box g, the outer end of the stem passing into a seat or bearing h, formed in the outer end of the bonnet. A spring i works in conjunction with the stem and normally holds the valve to its seat. The parts will be so arranged that the spring will hold the valve closed until a determinate pressure is exerted by the fluid hydrocarbon or gas, being regulated as desired by regulating the tension of the spring. A weight may be employed in lieu of the spring. The valve is provided with two longitudinally-extending slots j, in which are mounted the clearers or knives k, each knife being formed with a lug or finger l, which extends into a continuous groove or channel m. Similar knives n

are mounted in slots or ways formed longitudinally of the seat, the knives being formed with fingers *o*, which extend into a groove or channel *p*, formed in the valve. These knives or clearers fit into the slots or grooves gas-tight, so that when the valve comes to its seat the passage of gas or liquid hydrocarbon therethrough is prevented. From this it will be seen that a pair of the knives are always fixed against longitudinal movement, but may nevertheless move into and out of the ways or channels formed in the valve as the valve is moved to and from its seat, thereby insuring close and working contact between the knives and the valve-seat. The other pair will be moved back and forth with the valve, at the same time moving into and out of the ways formed in the valve-seat, this pair always maintaining close contact with the valve proper and working over its surface to keep it free of any accumulation of solid matter or deposit. As in the other form, a rocker-arm will be employed to impart rotary reciprocatory motion to the valve.

It is manifest that the clearers or knives may be carried by or mounted upon either part alone, and it is also manifest that but one knife or clearer may be employed, in either or both of which cases a continuous rotary motion may be imparted to the valve.

Having thus described my invention, what I claim is—

1. In combination with a suitable shell or casing having a discharge-orifice; a member movable into and out of said orifice to decrease or increase the space between the two; and means interposed between said parts for keeping the space between them free from accumulation of solid matter.
2. In combination with a valve and its seat, means interposed between said parts for keeping the space between the two free from accumulation of solid matter.
3. In combination with a valve and its seat,

a clearing device interposed between the same.

4. In combination with a valve and its seat, a clearing device interposed between the same; and means for imparting rotary motion to said valve.

5. In combination with a valve and its seat; a knife carried by the valve acting on the seat; and means for imparting rotary motion to the valve.

6. In combination with a valve and its seat, a pair of clearing devices carried by the valve; a second pair of clearing devices attached to the seat; and means for imparting rotary motion to the valve.

7. In combination with a valve and its seat, a pair of knives carried by the valve and movable toward and from the seat; and means for imparting rotary motion to the valve.

8. In combination with a valve and its seat, a pair of knives attached to the valve and movable radially toward and from the seat; a pair of knives attached to the seat and movable radially toward and from the valve; and means for imparting rotary motion to the valve.

9. In combination with a valve-seat having a groove or channel formed around the same; a pair of knives having a lug or projection extending from each into said groove or channel, said knives being mounted in ways formed in the valve-seat; a valve having a groove or channel formed around the same; a pair of knives having lugs or projections extending therefrom into said channel, said knives being mounted in ways formed in the valve; and means for imparting rotary reciprocatory motion to the valve.

In testimony whereof I have signed my name to this specification in the presence of two subscribing witnesses.

FRANK L. WAASER.
